UNITED STATES PATENT OFFICE

MAX S. GOLDSMITH, WALTER REES, AND RAYMOND O. WHEELER, OF CINCINNATI, OHIO,
ASSIGNORS TO THE BANKER'S CONSTRUCTION COMPANY, OF CINCINNATI, OHIO, A COR-
PORATION OF OHIO.

FURNITURE LEG AND APRON.

No. 909,887.

Specification of Letters Patent.

Patented Jan. 19, 1909.

Application filed October 7, 1907. Serial No. 396,216.

To all whom it may concern:

Be it known that we, MAX S. GOLDSMITH, WALTER REES, and RAYMOND O. WHEELER, citizens of the United States of America, and residents of Cincinnati, county of Hamilton, State of Ohio, have invented certain new and useful Improvements in Furniture Legs and Aprons, of which the following is a specification.

10 The object of our invention is a furniture leg and apron, especially for use in tables and desks, of a construction such that it may be packed in compact form for shipment and may be set up by the recipient with little labor, and which when so set up is of a firm construction. This object is attained by the means described in the specification and illustrated in the accompanying drawings, in which—

20 Figure 1 is a plan view of part of an apron and two of the legs of an article of furniture, embodying our invention. Fig. 2 is a perspective view upon an enlarged scale of the top of a leg and of the form of the apron at a corner. Fig. 3 is a perspective view of the top of a leg, the apron and a table or desk top. Fig. 4 is a sectional view taken upon line $v-v$ of Fig. 3.

25 Referring to the parts: The leg, A, is made of a tube, which is preferably rectangular in cross-section, and may be constructed from a sheet of metal bent to form a tube and having at its meeting edges inverted flanges locked by an angle strip, as illustrated in Fig. 2.

30 The apron, B, is made of a strip of metal which is bent outward at a right angle at its upper end to form a horizontal flange, b, and is bent inward at its lower end to form a horizontal flange, b'. The vertical member, b², of the strip is bent to form a right angle at the corner b³, the flange, b, being cut at b⁴, to permit the bending and the flange, b', being cut out, and the ends, b⁵, b⁶, thereof being turned upward into a vertical direction to fit against the external walls of the leg, A, as illustrated in Figs. 1, 3, and 4. The corner, a', of the leg which fits into the corner of the apron is strengthened by a

metal angle piece, C, which is held in place by means of rivets, e'.

The flange, b, is perforated at intervals to receive screws which are driven into the wooden top, D, of the table, or desk. The ends, b⁵, b⁶, are perforated and the leg, A, has perforations which register with the perforations in the ends, b⁵, b⁶, to receive screws to bind the parts together. Near the corner, b³, the vertical part, b², of the apron is perforated to register with screw-threaded perforations in the leg, A and the angle, C, to receive screws, e. In manufacturing a piece of furniture with which our apron and leg construction is used, such as a table or desk, for shipment, a rectangular apron may be 65 made in two pieces, each consisting of a side piece, I, two corners, b³ and two half sides, 2. The half sides, 2, may be then joined together by a metal strip, F, such as shown in Fig. 1. Then the top, D, is secured upon this rectangular apron by passing screws through the flanges, b, upward into the top. The rectangular legs, A, are then wrapped with paper and laid in the receptacle formed by the inverted top and 75 apron. It is seen that this forms a package which occupies little space as compared with the space occupied by a table or desk to which the legs have been attached. When the purchaser receives the goods, to assemble 80 the parts, he has only to slip the legs into the sockets formed by the corners, b³, the top, D, and the upturned ends, b⁵, b⁶, of the flanges, b', and to insert the screws into the flanges, b⁵, b⁶ and through the perforations in the 85 corners, b³. The leg will then be braced in a manner such as to prevent spreading or loosening of the same.

What we claim is:

1. A furniture leg and apron consisting of 90 an apron made from a strip of metal bent outward near its upper edge and inward near its lower edge to form horizontal flanges, the strip being bent at intervals to form corners and the lower flange being cut 95 away at the corners, and legs fitting into the sockets formed by the corners and the cut-away flanges.

2. A furniture leg and apron consisting of an apron made from a strip of metal, bent outward near its upper edge and inward near its lower edge to form horizontal flanges and bent at the corners to form leg sockets, the lower flanges being cut at the corners and the ends bent so as to stand in vertical planes, forming together with the

corners sockets for the legs and legs rectangular in cross-section to fit into the sockets. 10
